UNITED STATES PATENT OFFICE

111,561

DESIGN FOR A DRESS ENSEMBLE

Samuel Reich, Chicago, Ill.

Application August 20, 1938, Serial No. 79,464

Term of patent 3½ years

To all whom it may concern:

Be it known that I, Samuel Reich, a citizen of the United States of America, residing in Chicago, in the county of Cook and State of Illinois, have invented a new, original, and ornamental Design for a Dress Ensemble, of which the following is a specification, reference being had to the accompanying drawing, forming part thereof, wherein,

I claim:

The ornamental design for a dress ensemble, substantially as shown.

SAMUEL REICH.
